UNITED STATES PATENT OFFICE.

WILLIAM W. WATTERS, OF NEW ROCHELLE, NEW YORK.

INTERCHANGEABLE-INITIAL PLATE.

1,387,217.

Specification of Letters Patent. Patented Aug. 9, 1921.

Application filed October 19, 1920. Serial No. 417,907.

To all whom it may concern:

Be it known that I, WILLIAM W. WATTERS, a citizen of the United States, and a resident of New Rochelle, county of Westchester, 5 and State of New York, have invented certain new and useful Improvements in Interchangeable-Initial Plates, of which the following is a specification.

This invention relates to initial plates 10 such as are used on automobiles.

The objects of the invention are to provide a device of this character which will be ornamental and attractive in appearance, relatively simple and inexpensive, which can 15 be readily secured in position and in which the initials or other members will be readily interchangeable.

In the drawing accompanying and forming a part of this specification, I have illustrated the invention embodied in a simple 20 preferred form, but wish it understood that the same may be modified in certain respects without departure from the true spirit and scope of the invention as hereinafter defined and claimed.

Figure 1 of the said drawing is a front or face view of the complete device.

Fig. 2 is a longitudinal sectional view of the same on an enlarged scale, and showing 30 one method of applying the same to a desired support, this view being taken substantially on the plane of the line 2—2 of Fig. 1.

Fig. 3 is a transverse of vertical sectional view as taken substantially on the plane of the line 3—3 of Fig. 1.

Fig. 4 is a similar view illustrating a different means of mounting.

Fig. 5 is a detached perspective view of 40 the spring fastening bolt employed in Fig. 4, and Figs. 6, 7 and 8 are broken detail views.

The interchangeable initial members which are designated 7 are in the form of plates 45 bearing the desired letters, numerals or the like, and having their upper and lower shoulders cut back, or reduced as indicated at 8 in Fig. 3, so as to bring their faces flush with the supporting frame 9.

50 This frame is relatively thin, is of open construction and has inwardly extending flanges 10 at the front thereof to confine the initial members therein.

The interchangeable members are designed 55 entirely to fill the frame. To allow for a certain latitude of use, I have

shown the frame of a length to hold four initial plates. Ordinarily only three initial plates will be required, and in such a case, the fourth space may be closed by a blank 60 plate or as shown in the illustration by two blank plates 11, half the size of the initial plates and positioned preferably at the opposite ends of the monogram.

After the initial plates have been slipped 65 into the frame in the proper order, a backing plate 12 is preferably slid longitudinally into the frame over the backs of the initial plates so as to hold the same in their pre-arranged relation while the frame is being 70 engaged with the supporting base plate.

This supporting base plate is designated 75 13 and is shown as shouldered or undercut at its upper and lower rearward edges at 14 to receive the inturned longitudinal upper 80 and lower flanges 15 at the back of the frame. The base plate is also shown as shouldered or undercut at one end at 16 in Fig. 2, and the frame as having a rearward inturned flange 17 at this end to interlock 85 beneath the same. At the opposite end of the frame the flanges are interrupted, or in other words, the frame is left open at this point as shown at 18 so that it can be slid lengthwise over the base plate. When so 90 engaged over the base plate, it is preferably held in this position by means of a catch provided by a spring lip 19 which snaps over the adjoining end of the base plate.

Thus when the letters are assembled in 95 the frame and the frame is slipped lengthwise over the base plate into the final position where the frame covers and conceals the base plate, the parts will interlock to hold them in this position. Should it become necessary, however, to open the frame for the purpose of changing the letters or the like, this can be done by springing the lip 19 away from the adjacent end of the base plate and then slipping one part longitudinally with respect to the other part,—this action being facilitated by the engagement of a suitable tool with a notch 20 provided in the back of the base plate near the end thereof.

100 The base plate may be attached to its support in various ways, and for this purpose I ordinarily employ a fastening bolt having a square or angular shank which preferably is tapered rearwardly so as to fit snugly into 110 the seat or opening provided therefor.

This bolt is shown in Figs. 2 and 3 in the

form of a screw bolt 21 having an angular head 22 seated in a countersunk angular portion 23 in the front side of the base plate and an angular rearwardly tapering shank 24 5 projecting rearwardly through an angular opening 25 in the base plate.

This form of fastening is usually employed where the bolt must pass through a metal sheathing 26 and through a wooden or other 10 reinforcement 27 at the back of such sheathing. In such a case the angular corners of the tapered shank cut into the metal of the sheathing more or less and hence serve to hold or anchor the bolt and the base plate 15 carried thereby against turning.

The fastening illustrated in Figs. 4 and 5 is intended primarily for use where the bolt need pass only through a metal wall and cannot be conveniently engaged at the inner 20 end. This fastening consists of a spring metal bolt having an angular head 28 seated in the angular recess in the base plate and rearwardly projecting tapered spring arms 29 which are forced rearwardly through the 25 angular opening 30 provided in the metal supporting wall 31, said arms being bowed outwardly as indicated at 32, so as by their spring action to interlock with the supporting wall when forced in the position shown 30 in Fig. 4.

In Fig. 8, which is an enlargement of the lower portion of Fig. 3, I have shown how the flange 15, at the back of the frame is thinner than the undercut portion at the rear of the 35 base plate, so that there will be a slight clearance between the frame and the support to which the device is attached. This enables the frame to be readily slid endwise over the base plate after the base plate has been 40 affixed to the support and prevents the frame from scratching the support as the same is being slid into place. This view also illustrates how the undercut portions at the back of the base plate may be inclined or cut on a 45 bevel so as to operate as wedges to force the parts into what is practically a solid mass.

In this view I have further shown how a rounded groove or channel 35 may be formed 50 interiorly in the body portion of the frame between the front and back flanges to receive the edge of the backing plate 12 and the reduced edge of the base plate. This groove is shown as slightly wider than the two elements which it receives so as to assist in the 55 forward wedging action referred to.

The base plate may, if found desirable, be provided with screw holes such as I have shown at 33 in Fig. 6, enabling the same to be secured by screws in place of or in addition 60 to the securing bolt described.

In Fig. 7 I have shown the base plate 12 as having recesses 34 at its ends, which enable the insertion of a tool point into engagement with the letter plates at the end of the 65 frame to force said plates firmly to their

seats. The forward end of the backing plate may be beveled, if desired, to enable it to pass readily over the letter plates.

The base plate preferably matches the open end of the frame, as shown in Fig. 2, 70 so as to form in effect a rearward continuation of the end of the frame so that both ends of the device will be fully closed. In this view, the base plate is also shown as provided with a slight projection or lug 36 over which 75 the tongue 19 at the end of the frame will snap to secure the parts together. The open end of the frame is preferably cut down to a point substantially in line with the groove 35 in the opposite sides of the frame. 80

What I claim is:

1. The combination of a base plate having under-cut longitudinal edges at the back thereof, means for supporting said base plate on a desired object, a relatively thin open 85 frame having inwardly extending confining flanges at the front thereof, a plurality of selected members filling the frame and bearing against said flanges, said frame having inturned flanges at the back thereof to slide 90 beneath the undercut edges of the base plate, which flanges are interrupted at one end of the frame to enable the frame with the members in position therein being slid into position covering the base plate and said frame 95 being provided at the open end referred to with a catch interlocking over the adjacent end of the base plate when the frame is shifted into position fully covering the base plate. 100

2. The combination of claim 1 with shoulders on the frame and base plate interlocking when the frame is positioned over the base plate to secure said parts in such relation.

3. The combination of claim 1 with a 105 spring lip provided at the open end of the frame to snap over the adjacent end of the base plate when the frame is slid into position thereover.

4. The combination of claim 1 with a back- 110 ing plate interposed between the elements and the base plate and arranged to hold the elements in the frame while the frame is being slid over the base plate.

5. The combination of claim 1 with a back- 115 ing plate interposed between the elements and the base plate and arranged to hold the elements in the frame while the frame is being slid over the base plate, said backing plate having a beveled edge at the forward 120 end thereof to thrust the members outward in the frame against the confining flanges aforesaid.

6. The combination of claim 1 wherein the supporting means consists of an element 125 having a tapered angular shank held against turning in the base plate and arranged to prevent turning of the base plate with respect to the support.

7. The combination of claim 1 wherein 130

the supporting means consists of an element having a tapered angular shank held against turning in the base plate and arranged to prevent turning of the base plate with respect to the support, said shank being made up of spaced spring arms.

8. A device of the character described comprising a base plate having an angular sided opening therethrough provided with 10 a countersunk portion at the front of the base plate, a fastening bolt having a head seated in said countersunk portion and a rearwardly tapering angular shank projecting through said angular opening, said base 15 plate having further undercut parallel edges, a thin open frame having inwardly extending confining flanges at the front thereof and inwardly extending flanges at the rear thereof to engage beneath the undercut edges 20 of the base, and selected members held in the frame between the base plate and the confining flanges aforesaid.

9. A device of the character described comprising a base plate having an angular sided opening therethrough provided with 25 a countersunk portion at the front of the base plate, a fastening bolt having a head seated in said countersunk portion and a rearwardly tapering angular shank projecting through said angular opening, said base 30 plate having further undercut parallel edges, a thin open frame having inwardly extending confining flanges at the front thereof and inwardly extending flanges at 35 the rear thereof to engage beneath the undercut edges of the base, and selected members held in the frame between the base plate and the confining flanges aforesaid, and a backing plate at the rear of the selected members and between said members and the base 40 plate.

10. In a device of the character described, a base plate adapted to be secured to a support and having undercut rearward edges, 45 a frame adapted to receive interchangeable initial plates and having flanges to engage over the undercut edges of the base plate, said frame being partly open at one end to enable endwise engagement of the same over 50 the base plate and provided at said end with a spring lip, and a lug on the forward face of the base plate positioned to be engaged by said spring lip.

11. In a device of the character described, 55 a base plate adapted to be secured to a support and having undercut rearward edges, a frame adapted to receive interchangeable initial plates and having flanges to engage over the undercut edges of the base plate, 60 said frame being partly open at one end to enable endwise engagement of the same over

the base plate, said base plate being arranged to support the rearward flanges of the frame free of contact with the support to which the base plate is applied.

65

12. In a device of the character described, a base plate adapted to be secured to a support and having undercut rearward edges, a frame adapted to receive interchangeable initial plates and having flanges to engage over the undercut edges of the base plate, 70 said frame being partly open at one end to enable endwise engagement of the same over the base plate, said frame further having an internal groove formed in the body of the 75 same forward of the rear flanges aforesaid to receive the edge of the base plate.

13. In a device of the character described, a base plate adapted to be secured to a support and having undercut rearward edges, a 80 frame adapted to receive interchangeable initial plates and having flanges to engage over the undercut edges of the base plate, said frame being partly open at one end to enable endwise engagement of the same over 85 the base plate, said frame further having an internal groove formed in the body of the same forward of the rear flanges aforesaid to receive the edge of the base plate, and a backing plate interposed between the initial 90 plates and the base plate and received in said groove.

14. In a device of the character described, a base plate adapted to be secured to a support and having undercut rearward edges, 95 a frame adapted to receive interchangeable initial plates and having flanges to engage over the undercut edges of the base plate, said frame being partly open at one end to enable endwise engagement of the same over 100 the base plate, and a backing plate interposed in the frame between the initial plates and the base plate and having a recess at one or both ends of the same.

15. In a device of the character described 105 a base plate adapted to be secured to a support and having undercut rearward edges, a member to fit over said base plate and having flanges to engage behind the under-cut edges of the base plate, said member being partly open at one end to enable endwise engagement of the same over the base plate 110 and provided at said end with one element of a spring catch, the companion element of said spring catch being located on the base 115 plate in position to be engaged by and interlocked with the first element when the member is slid endwise over the base plate.

In witness whereof, I have hereunto set my hand this 14th day of October, 1920.

WILLIAM W. WATTERS.
